Primary Examiner — Dana K Weiland*Assistant Examiner* — Messina L Smith(74) *Attorney, Agent, or Firm* — Adam K. Sacharoff;
Much Shelist, P.C.**(57) CLAIM**

The ornamental design for a pan, as shown and described.

DESCRIPTION

FIG. 1 is a front side perspective view of a pan showing the new design;

FIG. 2 is a bottom perspective view thereof;

FIG. 3 is a left side view thereof;

FIG. 4 is a right side view thereof;

FIG. 5 is a front view thereof;

FIG. 6 is a rear side view thereof;

FIG. 7 is a top plan view thereof; and,

FIG. 8 is a bottom plan view thereof.

The broken lines shown in the drawings depict portion of the pan that form no part of the claimed design.

1 Claim, 6 Drawing Sheets(56)
